(57) **CLAIM**

The ornamental design for a slipper, as shown and described.

DESCRIPTION

FIG. 1 is a top perspective view of a slipper showing my new design.

FIG. 2 is a top view of a slipper.

FIG. 3 is a bottom view of a slipper.

FIG. 4 is a left side view of a slipper.

FIG. 5 is a right side view of a slipper.

FIG. 6 is a front view of a slipper.

FIG. 7 is a rear view of a slipper; and,

FIG. 8 is a bottom perspective view of a slipper.

The broken lines in the drawings depict portions of the slipper that form no part of the claimed design.

1 Claim, 8 Drawing Sheets

FIG. 1

FIG. 2

FIG. 3

FIG. 4

FIG. 5

FIG. 6

FIG. 7

FIG. 8
